[57] CLAIM

The ornamental design for an alternate power supply
adapter for a battery-operated radio telephone, as
shown and described.

DESCRIPTION

FIG. 1 is a front elevational view of an alternate power
supply adapter for a battery-operated radio telephone
showing my new design;

FIG. 2 is a bottom plan view thereof;

FIG. 3 is a right side elevational view thereof, the left
side elevational view thereof being a mirror image;

FIG. 4 is a top plan view thereof, the broken line por-
tion being disclaimed as being environmental elements
and not part of the claimed design; and,

FIG. 5 is a rear elevational view thereof.
